UNITED STATES PATENT OFFICE.

GEORGE D. KILBERRY, OF DOWNTON, PENNSYLVANIA.

SUCTION ROLL.

Application filed March 15, 1924. Serial No. 699,421.

To all whom it may concern:

Be it known that I, GEORGE D. KILBERRY, a citizen of the United States, and a resident of Downingtown, county of Chester, and 5 State of Pennsylvania, United States of America, have invented certain new and useful Improvements in Suction Rolls, of which the following is a specification.

This invention relates to suction rolls for 10 paper making machinery.

As is well known, suction rolls are used in paper making machinery, such as Fourdrinier machines, for abstracting water from the paper lap. Rolls of this type are 15 very heavy and expensive in construction and difficulty has been encountered in properly supporting the rolls and maintaining the rolls and the suction boxes contained therein in proper alinement. Suction rolls 20 are often driven at high rates of speed and at such speeds the bearings often give way and must be frequently renewed. This, of course, is expensive not only on account of the labor and material expense involved but 25 also on account of the fact that the roll is out of commission during this repairing or renewing of bearings.

This invention has for its salient object 30 to provide a suction roll so constructed and so supported that the suction box in the roll will be at all times properly supported and properly alined.

Another object of the invention is to so 35 support a suction box in the roll that the box will operate effectively to extract moisture or water from the lap and will not get out of alinement with respect to the roll axis.

Another object of the invention is to so 40 support the suction rolls that the peripheral speed of the roll journals in the bearings will not be excessive and will not be so great as to cause the bearings to wear rapidly and break down.

Another object of the invention is to so 45 support suction rolls of the type described that the rolls can be driven directly without the necessity of a complicated gear drive.

Further objects of the invention will appear 50 from the following specification taken in connection with the drawings, which form a part of this application, and in which.

Fig. 1 is a longitudinal sectional elevation, 55 illustrating the construction of a suction roll embodying the invention.

Fig. 2 is an enlarged sectional elevation taken substantially on line 2—2 of Fig. 1.

Fig. 3 is an enlarged sectional elevation taken substantially on line 3—3 of Fig. 1.

Fig. 4 is an enlarged sectional elevation 60 taken substantially on line 4—4 of Fig. 1.

Fig. 5 is an elevational view taken on line 5—5 of Fig. 1.

Fig. 6 is an enlarged sectional elevation 65 partly broken away taken on line 6—6 of Fig. 1.

Fig. 7 is a longitudinal sectional elevation similar to Fig. 1 but showing another embodiment of the invention.

Fig. 8 is an enlarged sectional elevation 70 taken substantially on line 8—8 of Fig. 7, and.

Fig. 9 is a sectional elevation taken on line 9—9 of Fig. 7 and showing the means 75 for adjusting the suction box.

The invention briefly described consists of a suction roll structure comprising a perforated shell having heads secured to the ends thereof and hollow journals carried by said heads. These hollow journals are 80 mounted in stationary bearings, that is, bearings in which the outer element is non-rotatable. A suction box is mounted within the perforated shell and has secured to its ends trunnions or journals, at least one of which is hollow, the journals being mounted and supported in the hollow journals of the shells. In the particular embodiment of the invention shown, the heads at the ends of the shell are provided not only with circular 85 flanges for supporting the shell but are also provided at the inner ends with seats adapted to receive anti-friction bearings. These bearings are interposed between the shell journals or heads and the journals of the suction box. The bearings are preferably located as close as possible to the suction box so as to directly support it and reduce deflection to a minimum. The suction box is 90 held against rotation with the perforated shell. By means of this construction, the suction box and perforated shell are always maintained in alinement with respect to each other and since the shell journals have 95 a much smaller diameter than the diameter of the shell, the rotation of the shell at excessive speeds will not cause undue wear on the bearings as the peripheral speed of the journals in the bearings will not be as great as that of the shell. Furthermore, the 100

Further objects of the invention will appear 105 from the following specification taken in connection with the drawings, which form a part of this application, and in which.

Fig. 1 is a longitudinal sectional elevation, 110 illustrating the construction of a suction roll embodying the invention.

suction roll or perforated shell can be directly driven and does not require a complicated train of gearing. Further details of the invention will appear from the following description.

- Referring, first, to the embodiment of the invention shown in Figs. 1 to 6 inclusive, there is illustrated a perforated shell 10 having heads 11 and 12 secured to the ends 10 thereof in any suitable manner as by bolts 13. The heads 11 and 12 have formed thereon or secured thereto journals 14 and 15 which are mounted in stationary bearings 16 and 17 of any desired construction. It will be understood that these bearings are carried by the main frame or support for the machine and are in no way dependent on the suction box or the supporting means therefor.
- 20 The shell may be driven in any desired manner by connecting the driving element to one of the journals, preferably the journal 14.
- 25 A suction box 25 is mounted in the shell 10 and has connected to its ends shafts 21 and 22, at least one of these shafts, namely the shaft 22, being hollow. The shafts or journals 21 and 22 extend into the journals 14 and 15 and are supported therein by 30 bearings supplemental to the said bearings 16 and 17. The particular embodiment of the invention shown, anti-friction bearings 23 are provided, these being interposed between the journals 21 and 22 and suitable 35 seats formed on the heads 11 and 12. These anti-friction bearings may be differently located, but the construction shown has important advantages. The illustrated construction, with the bearings at the inner ends 40 of the journals, gives a very direct support for the suction box and reduces to a minimum any tendency for the box to deflect or get out of coaxial relation with the rotatable shell. Furthermore, as already pointed out 45 the journals 14 and 15 and the bearings 16 and 17 are made relatively small in diameter to reduce the surface speed to a safe amount. The anti-friction bearings, however, in order to have ample load-carrying capacity must 50 be relatively larger in diameter. With the peculiar construction shown, I am able to provide anti-friction bearings of any needed or desired diameter without in any way interfering with or affecting the diameter of 55 the bearings 16 and 17.
- Preferably the suction box 25 is carried by a casing or drum 20 to which are secured the aforesaid journals 21 and 22. The box and the casing may be formed integrally 60 as shown in Figs. 1 to 6, or they may be formed separately as will be hereinafter described. With the integral construction partitions 26 and 27 separate the suction box proper from the casing.
- 65 The suction box is reinforced by cross

braces 28 and the central cross brace shown at 29 has a downwardly extending web 30 formed thereon.

The suction box has formed at its upper surface a longitudinally extending slot 31 and means are provided for forming a seal along both sides and across the ends of this slot. The suction box is otherwise entirely enclosed, so that air can enter only through those openings in the shell 10 which are momentarily over the slot.

As illustrated the sealing means includes deckle heads 33-33 which are adjustably mounted in longitudinal channels 32-32 formed at the ends of the suction box. The deckle heads are mounted on rods 34, the inner ends of which are threaded into lugs 35 extending upwardly from the end cross braces 28. The outer ends of the rods are suitably formed as shown at 36 to receive a tool by means of which the rods can be rotated to adjust the deckle heads in the channels 32 in which they are mounted. The adjustment of the deckle heads determines the effective length of the slot 31 in the suction box. The heads 11 and 12 of the shell 10 have suitable openings 37 to give access to the ends of the rods 34.

Channels 40 are formed in the suction box at the longitudinal edges of the slot 31 and in these channels are mounted fillers or packings 41 of any desired material, this material, however, being softer than the material of which the shell 10 is formed. Because of this fact in case the packings 41 engage the inner surface of the shell, the packings will wear and not the shell. However, in actual practice, these packings should be as close as possible to and not engage the shell.

The drum 20 and suction box formed therein are held stationary by means of an arm 45 illustrated in Fig. 1 as secured to the outer end of the suction box journal of shaft 22. This arm, as shown in Fig. 5, can be 110 adjusted at the desired angle by means of adjustable stops 46 and 47 threaded into lugs 48 secured to a part of the supporting standard for the fixed bearings.

An elbow 55 is coupled as shown at 56 to the outer end of the suction box journal 22 and to this elbow there is secured a conduit 57 which leads to a suitable suction pump for exhausting the suction box.

In Figs. 7, 8 and 9, there is illustrated a 120 slightly modified form of construction in which means is provided for adjusting the suction box toward or away from the inner surface of the perforated shell 10.

In this construction, the suction box proper is adjustably mounted in the drum or shell 20. The suction box in this case is formed separate from the drum 20 and consists of a longitudinally extending box having a downwardly extending elbow 61. A 130

flexible conduit, such as a rubber hose, 62 connects the elbow 61 with the inner end 63 of the hollow journal or shaft 64 at one end of the drum 20.

- 5 The suction box is adjustably mounted in the drum 20 in the following manner. A pair of bars 65 and 66 support the suction box and these bars are in turn supported in recesses 67 and 68 formed in inwardly 10 extending portions 69 of the drum. The bars are rigidly connected together by means of brackets 71. Each bar has secured thereto at spaced intervals, inclined guides 72 and the suction box rests on these guides. 15 The slots in the suction box engaging the guides are inclined to correspond with the inclination of the guides secured to bars so that as the bars are moved longitudinally, thus moving the guides, the suction box 20 will be raised or lowered as the case may be.

In order to move the bars longitudinally a lever 75 is pivoted at 76 to the drum 20 and has a pin and slot connection 77, 78 with one of the brackets 71. The opposite 25 end of the lever 75 extends through a slot 79 in the drum 20 and has connected thereto a rod 80 slidably supported in lugs 81 formed on the outer surface of the drum. This rod may be longitudinally adjusted in 30 any desired manner as by the rotation of a sleeve 82 threaded to the end of the rod and this sleeve may be reached through one of the openings 37 in the head 11 of the perforated shell. This adjustment of the suction 35 box is used only when the box is installed and at that time the box can be moved to the proper position with reference to the perforated shell. When the box has been so adjusted no further adjustment 40 should be necessary.

From the foregoing description, it will be seen that the suction roll or perforated shell and suction box are so mounted, that these two elements will be effectively supported 45 and will always be maintained in proper alignment with respect to each other. Furthermore, the method of supporting the perforated shell greatly simplifies the drive for the shell since it can be driven directly and 50 not through a complicated train of gears.

Although certain specific embodiments of the invention have been particularly shown and described, it will be understood that the invention is capable of modification and 55 that changes in the construction and in the arrangement of the various cooperating parts may be made without departing from the spirit or scope of the invention, as expressed in the following claims.

60 What I claim is:

1. The combination in a suction roll, of a non-rotatable suction box, a rotatable perforated cylindrical shell surrounding the suction box, two concentrically located journals connected with the ends of the shell,

two non-rotatable main bearings entirely independent of the suction box in which the journals are respectively supported, and supplemental bearings at the inner ends of the respective journals and close to the suction box for supporting the said box on the said rotatable journals. 70

2. The combination in a suction roll, of a non-rotatable suction box, a rotatable perforated cylindrical shell surrounding the suction box, two concentrically located journals connected with the ends of the shell, two non-rotatable main bearings entirely independent of the suction box in which the journals are respectively supported, journals for the suction box concentric with those for the shell, and anti-friction bearings each having one race carried by one of the first said journals and having the other race in engagement with one of the last said journals. 75

3. The combination in a suction roll, of a non-rotatable suction box, a rotatable perforated cylindrical shell surrounding the suction box, two concentrically located journals connected with the ends of the shell, two non-rotatable main bearings entirely independent of the suction box in which the journals are respectively supported, and anti-friction bearings at the inner ends of the respective journals and between the said main bearings for supporting the suction box on the said rotatable journals. 90

4. The combination in a suction roll, of a non-rotatable suction box, a rotatable perforated cylindrical shell surrounding the suction box, two concentrically located journals of relatively small diameter connected with the ends of the shell, two non-rotatable main bearings entirely independent of the suction box in which the journals are respectively supported, anti-friction bearings of larger outer diameters than the said journals and located at the inner ends thereof for supporting the suction box on the said rotatable journals. 105

5. In a suction roll, the combination of a rotatable perforated cylindrical shell, two similar separate heads at the ends of the shell, each comprising a journal concentric with the shell axis, a circular flange connected with the shell and a bearing seat adjacent the flange, two non-rotatable main bearings in which the journals are respectively supported, anti-friction bearings engaging the said bearing seats, and a non-rotatable suction box inside the shell and supported by the last said bearings. 115

6. In a suction box, the combination of two aligned pairs of separate concentric journals of which the outer are rotatable and the inner are non-rotatable, two main bearings supporting the outer journals respectively, supplemental bearings interposed between the outer and inner journals of the 120

130

- respective pairs at the inner ends thereof, with the ends of the shell, two non-rotatable main bearings in which the journals are respectively supported, a non-rotatable suction box inside the shell and entirely closed except where exposed to the shell, supplemental bearings carried by the journals for supporting the suction box, sealing means carried by the suction box and extending along both sides thereof in operative relation with the rotatable shell, and deckle heads carried at the ends of the suction box and longitudinally adjustable therealong. 70
5. 7. The combination in a suction roll, of a non-rotatable suction box, a rotatable perforated cylindrical shell surrounding the suction box, two concentrically located journals connected with the ends of the shell, of which at least one is hollow, two non-rotatable main bearings entirely independent of the suction box in which the journals are respectively supported, supplemental bearings carried by the journals for supporting the suction box, and means extending through the hollow journal for adjusting the suction box angularly on the last said bearings. 75
10. 8. The combination in a suction roll, of a non-rotatable suction box, a rotatable perforated cylindrical shell surrounding the suction box, two concentrically located journals connected with the ends of the shell, of which at least one is hollow, two non-rotatable main bearings entirely independent of the suction box in which the journals are respectively supported, supplemental bearings at the inner ends of the respective journals for supporting the suction box, and means extending through the hollow journal connected with the corresponding main bearing for adjusting the suction box angularly on the last said bearing. 80
15. 9. The combination in a suction roll, of a non-rotatable suction box, a rotatable perforated cylindrical shell surrounding the suction box, two concentrically located journals connected with the ends of the shell, of which at least one is hollow, two non-rotatable main bearings entirely independent of the suction box in which the journals are respectively supported, supplemental bearings carried by the journals for supporting the suction box, and means for adjusting the suction box radially with respect to the last said bearings. 85
20. 10. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means for adjusting the suction box radially with respect to the last said bearings. 90
25. 11. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means located entirely between the main bearings for adjusting the suction box radially with respect to the last said bearings. 95
30. 12. The combination in a suction roll, of a rotatable perforated cylindrical shell, two concentrically located journals connected with the ends of the shell, two non-rotatable main bearings in which the journals are respectively supported, a non-rotatable suction box inside the shell and entirely closed except where exposed to the shell, supplemental bearings carried by the journals for supporting the suction box, sealing means carried by the suction box and extending along both sides thereof in operative relation with the rotatable shell, and deckle heads carried at the ends of the suction box and longitudinally adjustable therealong. 100
35. 13. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means for adjusting the suction box radially with respect to the last said bearings. 105
40. 14. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means located entirely between the main bearings for adjusting the suction box radially with respect to the last said bearings. 110
45. 15. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means including longitudinally movable inclined guides for adjusting the suction box radially with respect to the last said bearings. 115
50. 16. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means including longitudinally movable inclined guides for adjusting the suction box radially with respect to the last said bearings. 120
55. 17. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means including longitudinally movable inclined guides for adjusting the suction box radially with respect to the last said bearings. 125
60. 18. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means including longitudinally movable inclined guides for adjusting the suction box radially with respect to the last said bearings. 130
65. 19. The combination in a suction roll, of a rotatable perforated cylindrical shell, two concentrically located journals connected with the ends of the shell, two non-rotatable main bearings in which the journals are respectively supported, a non-rotatable suction box inside the shell, supplemental bearings carried by the journals for supporting the suction box, and means including longitudinally movable inclined guides for adjusting the suction box radially with respect to the last said bearings. 135

with the ends of the shell, two non-rotatable main bearings in which the journals are respectively supported, a non-rotatable suction box inside the shell, supplemental bearings carried by the journals for supporting the suction box, and means for adjusting the suction box radially with respect to the last said bearings, the said adjusting means comprising two pairs of longitudinally movable inclined guides, operating rods connected with the guides, and a pivoted lever connected to move both rods.

17. The combination in a suction roll, of a rotatable perforated cylindrical shell, two concentrically located journals connected with the ends of the shell, of which at least one is hollow, two non-rotatable main bearings entirely independent of the suction box in which the journals are respectively supported, supplemental bearings carried by the journals for supporting the suction box, means for adjusting the suction box radially with respect to the last said bearings, an exhaust connection through the hollow journal, and a flexible pipe between the said journal and the suction box.

18. The combination in a suction roll, of

a rotatable perforated cylindrical shell, two concentrically located journals connected with the ends of the shell, two non-rotatable main bearings in which the journals are respectively supported, a long narrow suction box located inside the shell, a large non-rotatable cylindrical casing carrying and partly surrounding the suction box, and supplemental bearings carried by the journals for supporting the said casing.

19. The combination in a suction roll, of a rotatable perforated cylindrical shell, two concentrically located journals connected with the ends of the shell, two non-rotatable main bearings in which the journals are respectively supported, a long narrow suction box located inside the shell, a large non-rotatable cylindrical casing carrying and partly surrounding the suction box, supplemental bearings carried by the journals for supporting the said casing, and means for radially adjusting the suction box with respect to the casing.

In witness whereof, I have hereunto set my hand this 14th day of March, 1924.

GEORGE D. KILBERRY.
